UNITED STATES PATENT OFFICE.

CHARLES B. McDONALD, OF CHICAGO, ILLINOIS

MACHINE FOR CAPPING CANS.

SPECIFICATION forming part of Letters Patent No. 761,093, dated May 31, 1904.

Application filed December 17, 1902. Serial No. 135,540. (No model.)

To all whom it may concern:

Be it known that I, CHARLES B. McDONALD, a citizen of the United States, residing at Chicago, in the county of Cook and State of Illinois, have invented certain new and useful Improvements in Machines for Capping Cans, of which the following is a specification.

My invention is concerned with a novel machine for capping cans, in which the can after the cap or lid has been loosely placed thereon is inserted in the vacuum-chamber and the air is exhausted from around it, so that the cap or lid is forced securely in place.

To illustrate my invention, I annex hereto two sheets of drawings, in which the same reference characters are used to designate identical parts in all the figures, of which—

Figure 1 is a side elevation of the complete machine embodying my invention. Fig. 2 is a top plan view of the same. Fig. 3 is a side elevation of the upper part with the vacuum-chamber and the upper portion thereof in central vertical section. Fig. 4 is a detail in section on the line A A of Fig. 2 looking in the direction of the arrow, and Fig. 5 is a detail view of the gear-pinion and arm to raise the closure.

The machine or apparatus is mounted upon a standard 10, which is of the size and shape adapted to support the elements hereinafter mentioned within easy reach of the ordinary operator. As shown, it consists mainly of a base-piece and a vertical pillar extending vertically upward therefrom, the upper end of which is bent to the left, as shown in the drawings, and is provided with an angular passage 11, (see Fig. 3,) which opens through the aperture 12 into the bell-shaped vacuum-chamber 13, which is secured by the cap-screws 14 against the bearing-face of the top of the standard, a suitable rubber ring or gasket 15 being interposed between the two bearing-faces to make the connections air-tight, so that if the air is exhausted through the passage 11 it will be exhausted in the vacuum-chamber 13. Secured upon the left-hand side of the standard 10 some distance beneath the vacuum-chamber is a bracket 16, which has the vertical bearing-sleeve 17

formed thereon, in which slides the vertically-reciprocating rod 18, the upper end of which has the plate or table 19 secured thereon, having its upper surface adapted to contact with the rim of the vacuum-chamber 13 and form an air-tight closure therefor, this being facilitated by the employment of a rubber ring or gasket 20, which is secured to the under surface of the rim or bottom of the vacuum-chamber and against which the closure bears to form an air-tight connection or seal. This plate 19 has formed in or on the upper surface thereof the depression 21, (shown in dotted lines in Fig. 1,) which is adapted to accurately position the can 22 placed thereon, although it will be apparent that catches or other upwardly-projecting lugs might be employed instead of the depression. When the can is in position with the cap 23 loosely placed thereon, the operator places his foot upon the treadle 24, which is pivoted at 25 to a suitable bearing-lug 26 on the base of the standard and which has pivoted thereto at 27 the link 28, the upper end of which is secured to the valve-arm 29 in the manner to be subsequently described. Mounted in a bearing-ear 30 (see Fig. 3) is a pintle or shaft 31, which has journaled or secured thereon the gear-pinion 32, which meshes with a rack-bar 33, mounted to slide upon the link 28 and to reciprocate freely in the guide-piece 34, secured upon the standard 10. The gear-pinion 32 has rigidly secured to one side thereof the arm or lever 35, the upper surface of which cooperates with the lower end of the rod or plunger 18, which is preferably provided with the antifriction-roller 36. It will be apparent that as the treadle 24 is depressed the table 19 will be raised by the intermediate mechanism just described to the dotted-line position shown in Fig. 1, in which the can is inclosed within the vacuum-chamber, which is rendered air-tight by the pressure of the helically-coiled expanding spring 37, interposed between the collar 38, rigidly secured on the link 28, and the top of the rack-bar 33. This effect is produced by the fact that the stroke of the treadle 24 is greater than the amount necessary to raise the plate 19 high enough to close the

vacuum-chamber, and the resulting pressure of the spring 37, which is compressed after the vacuum-chamber is closed, serves to hold the plate securely in place and render the vacuum-chamber air-tight.

Leading to a continuously-operating air-pump or other source of reduced air-pressure or vacuum is a pipe 39, which is connected by a suitable air-tight union 40 with the short 10 connecting-pipe 41, which has the three-way valve 42, mounted to rotate in a suitable casing 43, which has the oppositely-disposed portions of the pipe 41 screwed into it together with the port 44, formed in the top thereof. The 15 portion of the pipe 41 next to the machine is connected by the elbow-shaped unions 45 and 46 with the passage-way 11, and the valve 42 has secured thereto the arm 29, which is pivotally connected, as at 47, to the upper end of 20 the link 28, which is slotted, as seen at 48, in order that the position of the pivotal connections 47 may be adjusted as may be necessary to obtain the desired movement of the valve 42 when the treadle 24 is depressed. A plunger 49 is mounted to reciprocate in the way 25 50, formed in the vertical extension 51 of the vacuum-chamber. The plunger is, as shown, grooved at one portion to prevent the air being confined in the upper end of the extension 51. 30 The lower end of the plunger 49 is provided with a plate 52, which fits loosely in the body of the chamber 13 and which may be supplied with one or more apertures 53 to permit the escape of the air through it as the plunger is 35 raised. Two or more pins 54 are placed on the inner wall of the vacuum-chamber to prevent the plate from moving out of the chamber.

The operation of the device will be readily apparent. The parts being in the position 40 shown in Fig. 1, the treadle is depressed, and the first movement thereof causes the plunger 18 to be raised, carrying the jar or can 22 into the chamber and closing the bottom thereof. The movement to the closing-point is not suf- 45 ficient to move the valve 42 enough to exhaust the air; but when the chamber is closed the continued movement of the valve which is permitted by the compression of the spring 37 serves to connect the chamber to the 50 vacuum and the air is exhausted therefrom. The cap 23 has been loosely placed on the can, and the weight of the plunger 49 and the plate 52 resting on the top of the cap is sufficient to hold the cap in place; but the weight of 55 the plunger and plate in pounds is less than fifteen times the number of square inches in the surface of the cap, so that the cap will not be held down so tightly that any air in the jar cannot be withdrawn. When the 60 treadle is released, the movement of the parts is reversed and the plate and plunger follow the can downward, holding the cap in place until the air is admitted to the vacuum-chamber, when of course the pressure of the atmosphere serves to hold the cap securely on

the can or jar with the customary atmospheric pressure of fifteen pounds to the square inch.

While I have shown my invention as embodied in the form which I at present consider best adapted to carry out its purposes, 70 it will be understood that it is capable of modifications and that I do not desire to be limited in the interpretation of the following claims, except as may be necessitated by the state of the prior art.

What I claim as new, and desire to secure by Letters Patent of the United States, is—

1. A device of the class described comprising the vacuum-chamber normally open to the air, the movable member to close it and adapted to carry a loosely-capped can or jar into said chamber, a vacuum-pipe leading to said vacuum-chamber, a valve mechanism through which the vacuum-chamber is normally open to the atmosphere but which can be moved to connect the chamber with the vacuum, and means for first closing the vacuum-chamber by the movable member and then automatically moving said valve mechanism to exhaust the chamber. 80

2. A device of the class described comprising the vacuum-chamber normally open to the air, the movable member to close it and adapted to carry a loosely-capped can or jar into said chamber, a plate in said chamber adapted to be raised by the cap of the can as the chamber is closed, a vacuum-pipe leading to said vacuum-chamber, a valve mechanism through which the vacuum-chamber is normally open to the atmosphere but which can be moved to connect the chamber with the vacuum, and means for first closing the vacuum-chamber by the movable member and then moving said valve mechanism to exhaust the chamber. 95

3. A device of the class described comprising the bell-shaped vacuum-chamber normally open at the bottom, the vertically-movable plate to close it and adapted to carry a loosely-capped can or jar into said chamber, a vacuum-pipe leading to said vacuum-chamber, an interposed three-way valve through which the vacuum-chamber is normally open to the atmosphere but which can be moved to connect the chamber with the vacuum, and means for first closing the vacuum-chamber by the movement of the plate and then automatically moving said valve to exhaust it. 110

4. A device of the class described comprising the bell-shaped vacuum-chamber normally open at the bottom, the vertically-movable plate to close it and adapted to carry a loosely-capped can or jar into said chamber, a plate in said chamber adapted to be raised by the cap of the can as the chamber is closed, a vacuum-pipe leading to said vacuum-chamber, an interposed three-way valve through which the vacuum-chamber is normally open to the atmosphere but which can be moved to connect the chamber with the vacuum, and means for 125 130

first closing the vacuum-chamber by the movement of the plate and then moving said valve to exhaust it.

5. A device of the class described comprising the vacuum-chamber normally open to the air, the movable member to close it and adapted to carry a loosely-capped can or jar into said chamber, a vacuum-pipe leading to said vacuum-chamber, a valve mechanism through 10 which the vacuum-chamber is normally open to the atmosphere but which can be moved to connect the chamber with the vacuum, and means for first closing the vacuum-chamber by the movable member and then moving said 15 valve mechanism to exhaust the chamber, said means consisting of an arm connected to the valve, an arm coöoperating with said member, a treadle-rod, a link connected to both of said arms, and a yielding connection between said 20 link and the arm operating the movable member.

6. A device of the class described comprising the vacuum-chamber normally open to the air, the movable member to close it and adapted to carry a loosely-capped can or jar into 25 said chamber, a vacuum-pipe leading to said vacuum-chamber, a valve mechanism through which the vacuum-chamber is normally open to the atmosphere but which can be moved to 30 connect the chamber with the vacuum, and means for first closing the vacuum-chamber

by the movable member and then moving said valve mechanism to exhaust the chamber, said means consisting of the arm 29 connected to the valve mechanism, the arm 35 coöoperating 35 with the movable member, the treadle 24, the link 28 connected to said treadle and the arm 29, the collar 38 on the link, the sliding rack 33, the pinion 32 secured on said arm 35 and meshing with said rack, and the expanding 40 spring 37 interposed between the collar 38 and the rack 33.

7. In a device of the class described, a vacuum-chamber, a can-carrying closure adapted to seal the same, a plate fitting loosely in the 45 chamber in the path of the can, means to exhaust the air from said chamber, and means to open and close the air-exhaust and to close and open the closure.

8. In a device of the class described, a vacuum-chamber, a can-carrying closure adapted to seal the same, a plate fitting loosely in the chamber in the path of the can, valve mechanism to control the air-exhaust, and means to open and close the valve and close and open 55 the closure.

In testimony whereof I affix my signature in presence of two witnesses.

CHARLES B. McDONALD.
